UNITED STATES PATENT OFFICE

110,866

DESIGN FOR AN ILLUMINATED ADVERTISING DISPLAY SIGN

William Taylor Johns, San Antonio, Tex.

Application December 27, 1937, Serial No. 73,880

Term of patent 3½ years

To all whom it may concern:

Be it known that I, William Taylor Johns, a citizen of the United States, residing at San Antonio, in the county of Bexar and State of Texas, have invented a new, original, and ornamental Design for an Illuminated Advertising Display Sign, of which the following is a specification, reference being had to the accompanying drawing, forming a part thereof.

Fig. 1 is a front elevational view of an illumi-

nated advertising display sign, showing my new design;

Fig. 2 is a side elevational view thereof;

Fig. 3 is a top plan view; and

Fig. 4 is a sectional view taken on line A—A of Fig. 1.

I claim:

The ornamental design for an illuminated advertising display sign, as shown.

W. T. JOHNS.
